CLAIM

The ornamental design for a helical fluted forward and reverse rotation cutting tool, as shown and described.

DESCRIPTION

FIG. 1 is a top front perspective view of the helical fluted forward and reverse rotation cutting tool of the present invention;

FIG. 2 is a right side view thereof, the left side view being a mirror image thereof;

FIG. 3 is a front view thereof;

FIG. 4 is a front view thereof; and,

FIG. 5 is a rear view thereof.

1 Claim, 4 Drawing Sheets
